CONTAINERS FOR ROCKET-PROPELLED AND OTHER MISSILES

Richard Sutton Ransom, Holywood, and Mervyn Francis Wilson, Belfast, Northern Ireland, assignors to Short Brothers and Harland Limited, Belfast, Northern Ireland

Filed Mar. 2, 1959, Ser. No. 796,696
4 Claims. (Cl. 89—1.7)

The object of the invention is to provide for a rocket-propelled or other missile an improved form of container, which will serve to protect the missile against damage in transport or during storage prior to use, in conditions in which it may be subjected to rough handling or contact with other objects, or in adverse climate conditions.

A container for the aforesaid purpose, according to the invention, comprises a two-section rigid casing, one section being arranged to encase the missile, and the other section forming a base-member by which the missile together with said first-mentioned section may be mounted on a launching support, the first-mentioned section of the casing being detachable from the base-section thereof prior to launching.

A further feature of the invention is the provision within the first-mentioned section of the casing of a flexible envelope which, after removal of said first-mentioned section will constitute a temporary weather protection for the missile, said envelope being attached to the base-section of the casing and incorporating rip seams along which the envelope will disintegrate when the missile is fired.

One embodiment of the invention, as applied to a container for a guided-rocket propelled missile, is herein-after described with reference to the accompanying drawings, in which:

FIG. 1 is a partly sectional longitudinal elevation of the container, with a missile mounted therein upon the base-member section,

FIG. 2 is an enlarged longitudinal section of the rear part of the container, illustrating the manner of its support upon a launching stand,

FIG. 3 is a front elevation of the nose of the container, and

FIG. 4 is a detail, drawn to a larger scale, of the means employed for attaching the casing component to the base-member, as viewed on the section line IV—IV of FIG. 3.

As will be seen from the drawings, the casing component 10 encloses the whole of the missile, the body of which is indicated generally by the reference numeral 11, extending from the domed nose 101, to a more or less cylindrical after-part or skirt 102. One or more resilient cushioning pads 12 are provided in the forepart 101 to space the missile within the casing. The periphery of the skirt 102 is arranged to be attached by spring clips 13 to a sheet metal annulus 14 which is attached to the rim of an aluminum alloy or other metal disc 141 which closes the rear end of the casing and which constitutes the base-member. For lightness and strength, the casing 10 is conveniently fabricated from moulded glass-fibre resin laminates.

Within the casing 10 the missile is enclosed by a flexible envelope 15, of polyethylene or analogous material, which is secured in position by means hereinafter described, for the purpose of affording temporary protection after removal of the casing 10 from the base-member.

A shackle 103 and lifting handles 104, 104 are provided on the casing 10 as shown.

Attached to the inner face of the base-member disc 141 is a beam 16 which extends forwardly to a position approximately opposite the centre-of-gravity of the missile, where it is provided with a longitudinally slotted lug

2

161 in which is received a similarly slotted pin 17 attached to the body of the missile, supporting the latter when mounted on the launching stand, part of which is indicated at 18.

5 The rear end of said beam 16 incorporates a socket 162 which is adapted, when the base-member is mounted on said launching stand 18 to receive with a close fit a forwardly projecting spigot 19 which serves to support the beam on the stand and also incorporates conductor leads 20, 20 by which electrical connections may be made to the missile through suitable contacts on the opposing surfaces of the spigot 19 and the socket 162. Mounted on the underside of the beam 16 is a bracket 21 carrying locating lugs 22 for the after end of the 15 missile and providing an abutment for a shear pin linkage 23 by which the missile is attached to the base-member 14. The angular location of the base-member disc 141 about the axis of the spigot 19 is determined by the engagement of a subsidiary spigot consisting of a flattened peg 24 which is fixed to the stand 18. The peg 24 is received in a hole 142 in said disc 141, the diameter of which is equal to the width of the peg. The peg is enclosed by a sealed canister 241 which is fixed to the inner face of the disc 141 about said hole 142.

20 In the centre of the base-member disc 141 is detachably mounted a blow-out panel 25 which, when the missile is fired is immediately displaced by the thrust of the efflux gases. The flexible envelope 15 extends to the corrugated lip 143 of the annulus 14 of the disc 141, about which it is secured by an elastic cord or the like 26 wrapped around said rim. The envelope 15 is divided by rip seams 151, 151 into longitudinal panels at the forward extremities of which are attached cords 152, 152 which extend within the envelope to a hook 27 on the inner face of said blow-out panel 25, to which they are tied, and the arrangement is such that when the blow-out panel 25 is displaced on firing, the tension of the cords 152 is immediately effective to rip away the seamed panels, leaving the missile free without encumbrance by the envelope 15 as the motor thrust rises to the high value required to rupture the shear-pin and effect launching.

35 What we claim as our invention and desire to secure by Letters Patent is:

40 1. In a container for use in storage of a missile and for supporting the missile in position for firing on a launching support, the improvement comprising: an outer casing including a rigid base member for supporting the missile and adapted to be mounted on the launching support and a rigid cover member detachably secured to said base member and normally encasing said missile for storage, said rigid base member including a light metal disc having a sheet metal annular rim, said disc being apertured for the passage therethrough of locating members carried by the launching support, said disc having a blow-out panel therein adapted to be blown out of position by thrust of the efflux gases on firing of the missile; an inner casing secured at one end thereof to the sheet metal annular rim of said base member and 45 also encasing the missile, said inner casing being a flexible envelope providing temporary cover of the missile when said rigid cover member is removed, said flexible envelope having rip seams extending along at least a portion of its length from its end furtherest from said base member and defining rip panels at least in an area adjacent the forward end of the missile; and means connected to the rip panels of the flexible envelope and the base member whereby the flexible envelope is opened along said rib seals when the missile is fired.

50 2. The combination of claim 1 wherein said last-mentioned means includes rip cords secured to the rip panels of said envelope and to the inner face of the blow-out

panel in said base member whereby outward displacement of the blow-out panel causes said rip cords to rip said envelope along said rip seams.

3. The combination of claim 1 including a beam connected to said base member and extending in cantilever relationship thereto, and means at the end of said beam for suspension of the missile at a point near the center of gravity thereof. 5

4. The combination of claim 3 wherein said beam includes a socket in its end adjacent to its attachment to said base member, said socket being adapted for reception of a locating and supporting spigot carried by the launching stand. 10
